Patented July 22, 1975

235,975

DIGITAL CLOCK

Eugene J. Sulek, Richardson, Tex., assignor to
Texas Instruments Incorporated

Filed Dec. 12, 1973, Ser. No. 424,143

Term of patent 14 years

Int. Cl. D10—01

U.S. Cl. D10—15

Des. 235,975

PAGE 2

Fig. 2

Fig. 3

Fig. 4

FIG. 1 is a front, top and right side perspective view of a digital clock showing my new design;

FIG. 2 is a rear, top and left side perspective view thereof;

FIG. 3 is a left side elevational view thereof; and

FIG. 4 is a front elevational view thereof.

The bottom of the digital clock, not shown, is substantially plain and unornamented.

I claim:

The ornamental design for a digital clock, substantially as shown.
